[57] **CLAIM**

The ornamental design for a bowl, as shown and described.

DESCRIPTION

FIG. 1 is a perspective view of a bowl, embodying our new design;

FIG. 2 is a perspective view of an alternate embodiment of a bowl embodying the present design, which alternate embodiment is identical to the embodiment of FIG. 1 and FIGS. 3 to 8, except for the length of the upstanding straw portion;

FIG. 3 is a front elevational view of the bowl of FIG. 1;

FIG. 4 is a rear elevational view thereof;

FIG. 5 is a top plan view thereof;

FIG. 6 is a side elevational view thereof;

FIG. 7 is an opposite side elevational view thereof; and,

FIG. 8 is a bottom plan view thereof.
